UNITED STATES PATENT OFFICE.

NATHAN H. SUREN, OF NEEDHAM, MASSACHUSETTS, ASSIGNOR TO THE GAMEWELL FIRE-ALARM TELEGRAPH COMPANY, OF NEW YORK, N. Y., A CORPORATION OF NEW YORK.

ELECTRIC-SIGNAL RECORDER.

938,285.

Specification of Letters Patent.

Patented Oct. 26, 1909.

Application filed October 16, 1908. Serial No. 453,042.

To all whom it may concern:

Be it known that I, NATHAN H. SUREN, of Needham, county of Norfolk, State of Massachusetts, have invented an Improvement in 5 Electric-Signal Recorders, of which the following is a specification.

This invention relates to electric signal recorders for recording fire-alarm, police and other signals on a tape.

10 The invention has for its object to provide means for cutting or slotting the tape so as to form tongues, instead of marking or indenting or puncturing the tape as has heretofore been done, and to turn under the tongues or 15 fold them back upon the tape to produce holes therethrough. Also to so construct the cutting-tool that a V-shaped tongue will be cut by it, which, when turned back upon the tape will present a triangularly shaped hole 20 in the tape. Also to so arrange the cutting-tool that the V-shaped tongues will be formed and pointed in the direction of movement of the tape, so that they may be turned under or back upon the tape as the tape is moved 25 along. Also to provide means for forming holes through the tape of such shape as to indicate at a glance the direction the signal must be read, as for instance the holes may 30 have dissimilar end portions, thereby overcoming a serious difficulty incident to the employment of the usual means for marking, indenting, or puncturing the tape. Also to so construct a triangular cutting-tool that it will begin to cut the tape at the apex of its 35 triangular portion and will continue the incisions along the sides of the triangle while the tape is moved along, thereby permitting movement of the tape while the tape is being cut. Also to provide independent means for 40 lifting the cutting-bar immediately after it has been depressed by the electro-magnet, thereby immediately removing the cutting-tool from the moving tape to obviate tearing the tape. Also to provide actuating-means 45 for the cutting-bar operated by an electro-magnet, or by any one of several electro-magnets, which is adapted to depress said bar to cause the cutting-tool to cut the tape and then disengage it, permitting it to be 50 lifted by independent means provided for the purpose, whereby the cutting of the tape is accomplished at the beginning of the signal impulse, and the duration of the impulse has no effect upon the cutting oper-

ation. Also to provide improved releasing- 55 mechanism for the tape-moving train. Also to provide releasing-mechanism for the tape-moving train adapted to be operated to release said train by the actuating-lever which is employed to depress the puncturing-bar. 60 Also to provide improved restoring means for said releasing-mechanism, whereby it is restored at the end of a predetermined period of time.

Figure 1 is a side elevation of an electric 65 signal recorder embodying this invention. Fig. 2 is a plan view of the same. Fig. 3 is an end view of the same. Fig. 4 is a detail of the cutting devices, the cutting-tool being depressed. Fig. 5 is a detail similar to Fig. 70 4, the cutting-tool being raised but the actuating-lever therefor being in its abnormal position. Figs. 6 and 7 are front and sectional views respectively of the cutting-tool. Figs. 8 and 9 are details of the stop-arm for 75 the releasing-mechanism of the tape moving train. Fig. 10 is a detail of the releasing-lever and co-operating parts. Figs. 11 and 12 are plan and sectional views of the cut or 80 slotted tape, and Fig. 13 is a plan view of the tape showing a tongue of a modified form.

The recorder herein shown for the purpose of illustrating my invention is of the multiple pen variety, it being arranged for five 85 circuits. The receiving electro-magnets a , see Fig. 1, are arranged one above the other and are supported by an upright plate a' . The armatures a^2 are attached to pivoted armature-levers a^3 having arms a^4 extended 90 from them, which are connected by similar means with the upper ends of the actuating-levers b .

As here shown, the arms a^4 of three of the armature-levers, namely, the two lower armature-levers and the next to the upper armature-lever are connected by rods a^5 with bell-crank levers a^6 loosely mounted on the uppermost pivot-shaft, and said levers a^6 are connected by rods a^7 with three of the actuating-levers b . The arm a^4 of the middle armature-lever is connected by a rod a^8 with a bell-crank lever a^9 loosely mounted on the pivot-shaft above it, and said bell-crank lever is connected by a rod a^{10} with a bell-crank lever a^{12} , loosely mounted on the uppermost pivot-shaft, and said bell-crank lever a^{12} is connected by a rod a^{13} with one

of the actuating-levers *b*. The armature-lever which is connected with the uppermost pivot-shaft has its arm *a*⁴ extended upward and connected by a rod *a*⁴ with one of the actuating-levers *b*. Said actuating-levers *b* are mounted on a pivot-shaft *b*' and extend downward and are formed or provided near their lower ends with means for depressing a cutting-bar and also for operating the releasing-mechanism for the tape-moving train. The actuating-levers are moved one way by said electro-magnets and the other way by restoring-springs *b*² which are attached to them. As here shown, each actuating-lever has near its lower end a laterally extended pin *b*³ which extends over the top of and engages a dog on the cutting-bar, which it is designed to depress, and its lower end is formed to engage and depress a bar *c*, which is arranged horizontally beneath it and which is connected at its ends to the extremities of a pair of arms *c*' secured to a pivot-shaft *c*². The bar *c* is made long enough to extend from side to side of the set of actuating-levers so as to be engaged by all of them. A single arm *c*³ is secured to the pivot shaft *c*² which extends downward and is arranged to operate the releasing-mechanism for the tape-moving train, so that said train will be released by and upon the operation of any one of the actuating-levers. The bar *c* and arms *c*' to which it is connected and the arm *c*³ secured to the pivot-shaft *c*², constitute the starting-device for the tape-moving train of which the arm *c*³ serves as the starting-lever.

d represents one of the cutting-bars, see Figs. 4 and 5, there being one for each actuating-lever. They are arranged side by side and independently pivoted at *d*', so that they may be operated independently of each other. They are made alike or substantially so. Each bar has secured to its extremity a cutting-tool *d*², herein also termed a slotting-tool or marker, which extends below the bar and is arranged above a hole *e*' in a plate *e*, or table, over which the tape *f* is moved. As the cutting-bar is depressed the cutting-tool pierces the tape and enters the hole *e*'. The preferred form of cutting-tool which is herein shown consists of a shank having an inverted triangular pyramidal end *d*³, the vertex or point of which first engages the tape. Such a tool presents a triangular cutting face arranged oblique to the plane of the tape and is adapted to make two incisions in the tape which meet at a common point and thereby form a V-shaped or triangular tongue, represented at *f*', which when turned back upon the underside of the tape presents a V-shaped or triangular hole or slot in the tape, see Figs. 11 and 12. Such a hole has dissimilar ends. The triangular shaped tool is arranged with the apex of its triangle at the

forward end, so that the V-shaped tongues which are produced by its repeated operation, and the V-shaped holes which are formed by subsequently turning under said tongues upon the tape, are pointed in the direction of the movement of the tape. The hole *e*' is herein shown as square, but it may be of any other shape, and the cutting-tool when depressed enters said hole and forces the tongue into said hole, so that as the tape is moved along said tongue will engage the front edge of the hole and will be turned backward. It will be noted that the shape of the hole *e*' and the shape of the cutting-tool are different, and hence the plate *e* having the hole does not coöperate with the cutting-tool to cut the tape, but merely provides an opening to permit depression of the tool. The cutting-tool herein shown, or any equivalent thereof, which is adapted to cut the tape to produce tongues, possesses many advantages over a cutting-tool which is arranged to remove small pieces from the tape, particularly in that no die is required, and the necessity of keeping the punch and die sharpened so as to easily cut the tape is avoided.

No difficulty is experienced in sharpening the cutting-tool herein shown. By so shaping the tool that the holes which are produced by it in the tape by cutting or otherwise, have dissimilar ends, and arranging the tool in such manner that the holes are pointed in a certain direction, as for instance in the direction of movement of the tape, the direction for reading the signal is determined. This feature is of particular advantage in reading the tape after it has been detached from the register, as there is no danger of reading the signal backward as is the case with the ordinary punching register where circular holes are produced in the tape. By turning the tongues backward upon the tape always in the same direction incidental to the movement of the tape always in the same direction, said tongues will also indicate the direction for reading the signal even though the holes should have similarly shaped ends. In lieu of shaping the cutting-tool to form V-shaped tongues it may be formed with parallel sides and a V-shaped end to form tongues as shown in Fig. 13, which will be turned backward upon the tape.

My invention, therefore, includes any form of tool for cutting or perforating the tape which is made of such shape as to produce holes in the tape having dissimilar end portions so as to determine the manner or direction for reading the signal; and also comprehends the employment of a cutting-tool, as contrasted to a punching-tool, when arranged to produce tongues in the tape which may be turned back on the under side thereof and thereby form holes therein.

The cutting-bars d are adapted to be depressed, each by the operation of its own actuating-lever, and to be lifted by independent means, and, as herein shown, a spring d^{10} is attached to each bar for the purpose of lifting it when permitted to act. A dog d^4 is pivoted at d^5 to each cutting-bar, which extends above the bar a short distance, and each dog is arranged to be engaged by the pin b^3 on the adjacent actuating-lever for the purpose of depressing the bar. Each dog is restrained from movement in one direction as the pin b^3 passes over it, to thereby depress the bar, and is free to move in the opposite direction to permit the return of the pin after the bar has been raised. As herein shown, each dog is held in its normal elevated position against a pin d^6 on the bar bearing it, by means of a spring d^7 , and by means of said pin is restrained from movement in one direction and by means of said spring is permitted to yield for the return of the pin b^3 . When any one of the actuating-levers is moved on its pivot by the operation of its corresponding electro-magnet the pin b^3 borne by it is moved in the arc of a circle in the direction the dog is restrained from movement, and by engaging the top of the dog, which is herein shown as inclined, acts to depress the dog and the bar bearing it. This movement of the pin is sufficient to pass by and disengage the dog, whereupon the bar is immediately raised by the spring d^{10} . At the end of the signal-impulse the actuating-lever is returned to its normal position, and as the pin b^3 returns it passes over the dog and the latter moves on its pivot to permit such return movement of the pin. Therefore, it will be observed, that at the beginning of a signal-impulse the actuating-lever operates to depress the cutting-bar for the purpose of cutting the tape, and that immediately said bar is raised by independent means, so that the duration of the signal-impulse has no effect upon the operation of the cutting-bar.

g represents the upper tape-feeding roller which is freely revoluble and g' the lower tape-feeding roller which is positively driven. The upper roller is borne by a frame which is movable manually in any well-known or suitable manner for the purpose of lifting it from the tape whenever required. The roller g' is connected with and operated by a motor-driven train for the purpose of feeding along the tape, and as the latter rests on the plate e it will be observed that as it is fed along the tongue f' which are produced by the cutting-tool and which are projected into the hole e' , are turned under or folded against its under side, and as the tape having the tongues turned under it passes between the rollers g and g' , said tongues will be rolled down upon the tape. Any suitable train of gears

may be provided for positively driving the feeding rollers g' , one form being herein shown merely for the sake of illustration.

g^2 represents the escape-wheel for the train having thereon a stop-pin g^3 , which is adapted to be engaged by an arm g^4 of a pivoted releasing-lever, the other arm g^5 of which is adapted to be engaged by a pin g^6 on the main stop-arm g^7 . The releasing-lever is held in engagement with said stop-pin g^3 by a locking-lever, herein shown as a bell-crank lever, one arm g^8 of which bears a projection g^9 which is adapted to occupy a position back of the lower end of the releasing-lever to thereby hold said lever and the other arm g^{10} of which extends upward and is also adapted to be engaged by said pin g^6 on the main stop-arm. A spring g^{12} is connected to the releasing-lever which when permitted to act moves said lever to disengage the stop-pin g^3 and thereby release the train, and said spring is also connected to the locking-lever and acts to move said lever into its locking position. The single spring performing these two functions is herein employed merely for simplicity of construction. The end of the arm g^{10} of the locking-lever which engages the pin g^6 is beveled and as the pin g^6 is moved downward by the stop-arm it moves over the beveled end of the arm g^{10} and thereby moves the locking-lever sufficiently to cause the projection g^9 thereon to pass beneath the end of the arm g^4 of the releasing-lever and thereby disengage said releasing-lever. As the pin g^6 is moved downward it is also removed from engagement with the arm g^5 of the releasing-lever, so that the releasing-lever is permitted to operate as soon as disengaged by the locking-lever. As the pin g^6 is moved upward it engages the arm g^5 of the releasing-lever and restores the lever to its normal position and also permits the locking-lever to resume its normal position. As the releasing-lever resumes its normal position it is quite important that it shall instantly engage the stop-pin g^3 when brought into proper position instead of riding onto said pin gradually. To accomplish this result the arm g^4 is pivotally connected to the main body portion of the releasing-lever by a pivot-pin g^{30} , which permits lateral movement thereof, and the projection g^9 on the locking-lever is formed with an inclined side which is engaged by said arm and acts to move said arm laterally on its pivot until it passes over said projection. It then suddenly returns and in doing so moves directly beneath the stop-pin g^3 and enters a notch formed in the under side of said pin. A flat spring g^{31} is arranged on the releasing-lever which acts to return the arm g^4 as soon as said arm passes over the inclined projection g^9 . The stop-arm g^7 is pivotally mounted on the arbor g^{40} and is

movable thereon through an arc so that the pin g^6 is movable up and down a short distance only. To thus control and limit the movement of the stop-arm a pawl g^{13} is arranged thereon which engages a ratchet-toothed disk g^{14} herein shown as one of the side plates of the barrel containing the main spring. The pawl is movable into and out of engagement with said ratchet-toothed disk 5 and when in engagement therewith is moved upward by it to in turn raise the stop-arm and when disengaged from it the stop-arm is free to be depressed. A spring g^{20} is provided for depressing the stop-arm, which is 10 connected at one end with said arm and at the other end to an arm g^{21} bearing a pin g^{22} which engages the lower end of an adjustable pin g^{23} . The pawl is disengaged from the disk at the beginning of a signal impulse 15 and is permitted or caused to reengage the disk only at the end of the signal impulse and such movement of the pawl is controlled by the starting-lever c^3 , and as a result the train will be started at the beginning of a signal impulse and will not only run during 20 the continuance of said impulse, but will continue to run for a short period of time after said impulse has ceased.

As herein shown, the pawl has a laterally extended pin g^{15} which extends through and works in a slot g^{16} in the stop-arm and one end of a sliding-bar g^{17} is connected to said pin g^{15} which is supported in bearings on the stop-arm. Longitudinal movement of 30 said bar operates the pawl. The bar is provided at its opposite end with a laterally extended pin g^{18} which is engaged by the lower end of the starting lever c^3 , so as to be moved in one direction, as for instance, to disengage 35 the pawl from the disk, by said starting-lever whenever the latter is operated by any one of the actuating-levers b . A spring g^{19} is connected to the sliding-bar for the purpose of returning it when the starting-lever resumes its normal position. Thus the 40 pawl is moved out of engagement with the disk by the starting lever and is returned by a spring as soon as said starting-lever resumes its normal position. As soon as the 45 pawl reengages the disk it is moved upward by said disk, together with the stop-arm bearing it, until the pin g^6 has restored the releasing-lever and the locking-lever has resumed its locking position, at which time 50 the train is arrested.

If for any reason the means herein described for arresting the train should not properly operate, although the pawl engages the disk, a severe strain will be brought 60 upon the teeth of the disk and to obviate this the pawl g^{13} is provided with an extension g^{50} which is arranged to engage one of the shafts of the train, as shaft g^{60} , which 65 acts to disengage the pawl and permit the stop-arm to be again depressed, and such

action will repeatedly continue until the spring runs down or the train has been otherwise arrested. It will thus be seen that the pawl is repeatedly operated to disengage the disk upon the occurrence of the signal 70 impulses and that it reengages the disk upon the cessation of the impulses and that the train continues to run only for a short period of time after the pawl has reengaged the disk or until the releasing-lever has been 75 restored to normal position and the locking-lever has also been restored to normal position.

Having thus described my invention, what I claim as new and desire to secure by Letters Patent is:—

1. In a recorder, a cutting-tool having a cutting face formed with dissimilar end portions to produce holes in the tape having dissimilar ends, whereby the direction for 80 reading the signal may be determined, and means for operating said tool, substantially as described.

2. In a recorder, a cutting-bar bearing a cutting tool having a triangularly shaped 85 cutting face, and means for operating said bar to cause the tool to cut the tape, substantially as described.

3. In a recorder, a cutting-bar bearing a cutting-tool having a triangularly shaped 90 cutting face arranged with its apex pointed in the direction of movement of the tape, and means for operating said bar to cause the tool to cut the tape, substantially as described.

4. In a recorder, a cutting-bar bearing a cutting-tool having an inverted triangular pyramidal end, and means for operating said bar to cause the tool to cut the tape, substantially as described.

5. In a recorder, a cutting-bar bearing a cutting-tool having an inverted triangular pyramidal end arranged with the apex of the triangle pointed in the direction of movement of the tape, and means for operating 11 said bar to cause the tool to cut the tape, substantially as described.

6. A recorder including a marker adapted to slot the tape to form a tongue, and means to operate said marker, substantially as described.

7. A recorder including a marker adapted to form slots in the recording tape by means of a continuous cutting action and thereby forming depending tongues of paper, substantially as described.

8. In a recorder, a slotting-tool constructed to cut the tape to form a tongue, means for operating said tool, and means for moving the tape and for turning under the tongue as it is moved along, substantially as described.

9. In a recorder, a cutting-tool constructed to cut the tape to form a tongue having dissimilar ends, means for operating said

tool, and means for moving the tape and for turning under the tongue as it is moved along, substantially as described.

10. In a recorder, a cutting-tool constructed to form a triangularly shaped tongue on the tape, which is pointed in the direction of movement of the tape, means for operating said tool, and means for moving the tape and for turning under the tongue as it is moved along, substantially as described.

11. In a recorder, a cutting-tool constructed to cut the tape to form a tongue, means for operating it, a plate having a hole arranged beneath said tool which receives said tool when depressed and also the tongue, and means for moving the tape over said plate whereby the tongue is turned backward on the under side of the tape by engaging the edge of said hole, substantially as described.

12. In a recorder, a supporting-plate for the tape having a hole of a shape different from the cutting-tool and a cutting-tool having a triangular cutting face arranged oblique to the plane of the supporting plate, and means for operating said tool, substantially as described.

13. In a recorder, a supporting-plate for the tape having a hole of a shape different from the cutting-tool, tape-moving mechanism, a cutting-tool having a triangular cutting face arranged oblique to the plane of the supporting-plate and with its apex pointed in the direction of the movement of the tape, substantially as described.

14. In a recorder, a cutting-bar bearing a cutting-tool, electro-magnetically operated actuating-means for depressing it to cause the tool to puncture the tape and for then disengaging it, and independent means for lifting it to remove the tool from the tape as soon as the actuating-means disengages it, substantially as described.

45. 15. In a recorder, a cutting-bar bearing a cutting-tool, a dog pivoted to said bar which is restrained from movement in one direction but permitted to move in the opposite direction, an actuating-lever bearing a pin adapted to engage said dog which, upon a continuous forward movement of the lever, depresses said dog and the bar bearing it and then passes by and thereby disengages it, a spring connected with said bar for lifting it when the actuating-lever disengages the dog, and an electro-magnet for operating said actuating-lever, substantially as described.

16. In a recorder, the combination of a tape-moving train, releasing-mechanism therefor, a stop-arm for said releasing-mechanism, a pawl borne by it, a power driven ratchet-toothed disk into and out of engagement with which said pawl is movable and by which said stop-arm is returned to and

held in its normal position, substantially as described.

17. In a recorder, the combination of a tape-moving train, releasing-mechanism therefor, a stop-arm for said releasing-mechanism, a pawl borne by it, a power driven ratchet-toothed disk into and out of engagement with which said pawl is movable and by which said stop-arm is returned to and held in its normal position, and an electro-magnetically operated starting lever for operating said pawl, substantially as described.

18. In a recorder, the combination of a tape moving train, a releasing-lever therefor, a locking-lever for said releasing-lever, a stop-arm bearing a pin arranged when moved in one direction to operate the locking-lever and permit the operation of the releasing-lever and when moved in the opposite direction to restore the releasing-lever and permit the return of the locking-lever, and means for operating said stop-arm, substantially as described.

19. In a recorder, the combination of a tape-moving train, a releasing-lever therefor having a pivotally connected arm, a locking-lever for said releasing-lever having an inclined projection adapted to be engaged by said arm, a stop-arm and means operated by it for operating said locking-lever and for restoring said releasing-lever, and means for operating said stop-arm, substantially as described.

20. In a recorder, the combination of a tape moving train, releasing-mechanism therefor, a stop-arm for said releasing-mechanism, a pawl borne by it, a power driven ratchet toothed disk into and out of engagement with which said pawl is movable and by which said stop-arm is returned to and held in its normal position when the train is arrested, said pawl having an extension arranged to engage a fixed part to disengage the pawl from the disk, substantially as described.

21. In a recorder, the combination of tape-moving mechanism, releasing-mechanism therefor, a plurality of markers adapted to slot the tape, separate electro-magnetically operated actuating devices for said markers, and means common to all said actuating devices for operating said releasing-mechanism, substantially as described.

22. In a recorder, the combination of tape moving mechanism, releasing-mechanism therefor, a plurality of cutting-bars bearing cutting-tools for the recording-tape, electro-magnetically operated actuating-levers for said bars, respectively, and means, common to all said actuating-levers and connected with the releasing-mechanism, whereby said releasing-mechanism is operated by any one of said actuating-levers, substantially as described.

23. In a recorder, the combination of tape-

6

moving mechanism, releasing - mechanism therefor, a plurality of markers adapted to slot the tape, separate electro-magnetically operated actuating devices for said markers, and means common to all said actuating devices for operating said releasing-mechanism, and means for stopping said tape-moving mechanism when all the circuits connected with the recorder have remained normal for a predetermined period of time, substantially as described.

24. In a recorder, the combination of tape-moving mechanism, releasing mechanism therefor, a plurality of cutting bars bearing cutting tools for the recording tape, electro-magnetically operated actuating levers for said bars respectively, and means common to all said actuating levers and connected with the releasing mechanism whereby said releasing mechanism is operated by any one of said actuating levers, and means for stopping said tape-moving mechanism when all the circuits connected with the recorder have remained normally for a predetermined period of time, substantially as described.

25. In a recorder, the combination of tape-moving mechanism, releasing - mechanism therefor, a cutting - bar bearing a cutting - tool, electro - magnetically operated actuating - means for depressing said bar to cause the tool to puncture the tape and for then disengaging it, independent means for lifting the cutting - tool to remove it from the tape as soon as it is disengaged by the actuating - means, and means also operated by said actuating - means for operating said re-

leasing - mechanism, substantially as described.

26. A recorder including a cutting - tool adapted to slot the recording - tape, and a support for said recording - tape having an aperture of a shape different from the slot which is cut in the tape, into which said cutting - tool projects when slotting the tape, substantially as described. 40

27. A recorder including a slotting - tool adapted to form slots in the recording - tape, by means of a continuous cutting action, and a support for the recording - tape having an aperture of a shape different from the slot 50 formed in the tape, into which said slotting - tool projects when slotting the tape, substantially as described. 45

28. A recorder including a slotting - tool adapted to form slots in the recording - tape 55 by means of a continuous cutting action, and a support for the recording - tape having an aperture larger than the slot formed in the tape, into which said slotting - tool projects when slotting the tape, substantially as described. 60

29. A recorder including a pointed marker adapted to puncture the recording - tape and form slots therein by a continuous cutting action, substantially as described. 65

In testimony whereof, I have signed my name to this specification, in the presence of two subscribing witnesses.
